(57) **CLAIM**

The ornamental design for a power converter body, as shown and described.

DESCRIPTION

FIG. 1 is a perspective view of a power converter body, showing our invention.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The stippling indicates a contrasting color (e.g., black or dark gray or another color) of the stippled portion of the design relative to the color (e.g., metallic color or light gray or another color) of the non-stippled portion of the design.
